FLEXIBLE FLOOR MAT OR PLATFORM

Everett Edward Thompson, Sr., Lynwood, Calif.

Application January 26, 1946, Serial No. 643,526

3 Claims. (Cl. 20—78.6)

1

My invention relates to a flexible mat or platform for floors, decks, stairs, verandas, porches or for any other wooden or concrete surface to prevent slipping when traversed.

In particular my platform is intended for use in corridors, in restaurants, in stores, banks behind counters for clerks, tellers, barbers, cooks and so forth, to provide a smooth yielding and non-slipping surface to stand on or walk over. It has enough give or spring to it to take care of jolts while walking and give adherence enough to prevent slipping.

Being flexible and of suitable lengths, 6 to 20 feet, the platform can be rolled up for storing or for easy handling for cleaning. It can be scoured without injury, the materials used therefore being preferably a combination of wood and rubber.

One embodiment of the invention is illustrated in the accompanying drawings, wherein:

Figure 1 is a top plan view of the mat or platform with parts broken away;

Figure 2 is a side elevation of Figure 1 partly in section;

Figure 3 is a transverse section in larger scale of Figure 1 along line 3—3;

Figure 4 is an enlarged, fragmentary section along line 4—4 of Figure 1;

Figure 5 is a top plan view of the platform as suitable more particularly to fit an operation chair as used in a dentist's office or in a barber shop;

Figure 6 is a similar view of the platform for a kitchen in front of a cook stove;

Figure 7 is an enlarged, fragmentary section along line 7—7 of Figure 5.

The same reference characters in the different figures relate to the same details and numeral 10 represents two, three or more floor runners preferably made of rubber or similar flexible material of the full length, six to twenty feet, of the platform, and as here shown consisting of two side runners and a middle runner 10a. The runners constitute the base part of the platform, to rest on the floor.

In order to have desired spring or give to the platform, the outside runners 10 are preferably made thicker than the middle runners 10a which are $\frac{1}{16}$ " to $\frac{1}{4}$ " less than the outside runners 10 which are given a thickness of $\frac{3}{4}$ " to 1". To make up the difference, rubber washers 9 are inserted between the runner and overlying slat, Figure 3.

Transversely across the runners 10 and 10a are shown wooden slats 11. These slats are

5 preferably about two inches wide, $\frac{1}{2}$ " to $\frac{3}{4}$ " thick and three to four feet long as required for the width of the platform and placed about $\frac{1}{2}$ inch or more apart on the runners 10 to which they are firmly secured by rivets 15 or the like. At each end of the platform is placed, instead of slats 11, a wooden board 12 of greater width than the slats and provided with a stepped portion 13 having a chamfered or beveled outer edge 14. This end board serves to ease a person's entering on the platform without stumbling by striking his foot against the abrupt or square of a slat. Similarly the side edges of the platform Figure 3, have wooden boards 16 provided with 15 a beveled edge 17 and preferably removably secured by bolts 18 to the runner 10. The platform surface is about one inch or more above that of the floor and is quite smooth for easy walking thereon. It may be painted any desired 20 color to make it attractive.

Illustrations of some particular applications of this flexible floor mat will now be given.

In Figure 5 a dentist's or barber's platform is indicated as consisting of two mating halves A and B each with a semicircular indentation at 25 one end 21 adapted together to form a circle around the base of the chair. Along the two adjacent sides of each half platform a semi-circular rubber runner 22 will here be provided 30 to which the inner ends of the slats 11 are secured as before. Along the straight sides of both platforms from the semi-circle to the ends, a straight rubber runner 23 is also here provided as well as runner 10 along the outer sides of the 35 platforms. The latter sides are also here provided with a beveled wooden board 16, removably secured by a bolt 18 as in Figure 2 or a peg 19 as seen in Figure 7. Likewise the platform ends have beveled boards 12. Lastly in Figure 6 the 40 application of the invention for a kitchen is indicated, wherein numeral 25 an ordinary range or cook-stove, is indicated in front of which is placed a flexible platform C of my invention. As before this consists of runners 10 of rubber 45 and cross slats 11 of wood and beveled wooden boards 12 at each end. In this case however only one similar side board 16 is provided, but none on the side adjacent the stove 25, from 50 which side the cook is not likely to mount the platform.

It will now be evident that, in the case of each form of platform herein described, it can be rolled up for storage or cleaning after first removing the stiff wooden side boards 16.

Rubber belting is found to be most suitable

for the runners, but in case the same is not available, a flexible plastic material may be selected. For the slats flexible lumber is preferred.

It should be noted that in case of narrow mats or platforms which are only about two feet wide, a middle runner will not be used. The cross section will in that case be like that shown in Figure 3 by leaving out the middle runner 10a, leaving only the two side runners 10.

Regarding the example given in Figure 5 for mat or platform suitable for operation chairs, more particularly for barbers' chairs, it may at times be desirable to provide a substantially solid platform, that is to say that instead of spacing the slats 11 as indicated in said figure, the slats may be placed close together, the construction otherwise remaining the same as shown in Figure 5. This will not hinder rolling up of the mat or platform. As before the beveled side boards 16 are first removed, whereupon the mat will roll up tightly, but backwards, that is to say, with the underside innermost.

It is to be understood that the invention as here disclosed is not limited to the details here described and shown but that the same may be varied widely without departing from the spirit of the invention as defined by the subjoined claims.

I claim:

1. A floor mat comprising parallel flexible runners of equal length and spaced apart, a plurality of spaced parallel slats disposed transversely of said runners and terminally secured thereto, and inflexible side boards substantially coextensive in length with said runners and removably secured

thereto, the inner longitudinal edges of the side boards and the ends of said slats abutting along lines extending longitudinally and substantially medially of the runners.

- 5 2. A floor mat comprising parallel flexible runners of equal length and spaced apart, a plurality of spaced parallel slats disposed transversely of said runners and terminally secured thereto, and inflexible side boards substantially coextensive in length with said runners and removably secured thereto, the inner longitudinal edges of the side boards and the ends of said slats abutting along lines extending longitudinally and substantially medially of the runners, the upper surfaces of 10 the slats and the upper surfaces of the side boards being substantially co-planar, and the side boards having rabbets to receive the outer lateral portions of the runners.
- 15 3. A mat according to claim 2 and in which said side boards are bevelled on the outside edges, and end boards with similar rabbets and similarly bevelled secured to the ends of said runners transversely thereof.

EVERETT EDWARD THOMPSON, SR.
